ICE CRUSHING AND FEEDING DEVICE

Frank W. Brady, San Francisco, Calif.

Application June 9, 1945, Serial No. 598,539

5 Claims. (Cl. 241—60)

1

This invention relates to improvements in ice crushing and feeding devices.

The use of finely divided ice, sometimes termed "snow-ice," to refrigerate perishable commodities placed in trucks, refrigerator railroad cars and the like, is wide spread. Numerous perishable commodities are covered with a layer of finely divided ice at the time they are loaded for shipment and, while in transit, this layer of finely divided ice is frequently refreshed by the addition of ice to replace that which has melted. Because a body of finely divided ice solidifies if stored for any length of time, and because of the necessity of moving the ice supply to the vehicle in which the ice is to be placed, I have previously developed a device in which ice was crushed in an ice crusher and, immediately thereafter, conveyed, either in a flowing airstream produced by an auxiliary blower or by application of force from a separate device, to its point of use through a hose or other conduit.

The present invention relates to an improvement upon this device in that the ice crusher drum and the wheel utilized to impart the force are provided upon the same shaft, thus simplifying the construction materially for only two bearings and one shaft are required in place of two shafts, four bearings and a separate feeder means for transporting the ice from the crusher into the wheel or blower.

As an additional advantage, the construction of the device of the present invention enables the ice to be fed into the device at a materially lower height above the floor level, thus simplifying and reducing the amount of labor required to introduce the heavy ice chunks or blocks into the ice crusher.

To enable the crusher drum and wheel to be mounted on the same shaft, I have found it necessary that the diameter of the drum and the diameter of the wheel be properly related and that a certain minimum critical ratio between these must be observed.

It is in general the broad object of the present invention to provide an improved ice crushing and blowing device.

A further object of the present invention is to provide a device in which the ice crushing drum and the means for moving the ice are mounted upon a common shaft.

The invention includes other objects and features of advantage, some of which, together with the foregoing, will appear hereinafter wherein the present preferred form of ice crushing and blowing device is disclosed. In the drawing accompanying and forming a part hereof,

Figure 1 is a side elevation, partly in section, through a device of the present invention.

Figure 2 is an end view of the device shown in Figure 1.

2

In accordance with this invention, I provide a suitable base 6 having wheels 7 thereon, the front wheel being movably mounted as at 8, and adapted to be drawn over the floor by a handle 15. Supported from the truck 6 by a plurality of vertical angle irons 9, is a housing, generally indicated at 11, and provided by several metal plates suitably welded or otherwise joined together. Bearings 12 and 14 are provided upon opposite sides of the housing and a shaft 16 is mounted in these bearings and carries an ice crushing drum generally indicated by numeral 17, and a centrifugal runner or wheel generally indicated by numeral 18.

15 The housing 11 is mounted at such an angle to the horizontal that the axis of shaft 16 is inclined at 45° to the vertical. By positioning the shaft at an angle of 45°, the rate of reduction of ice is increased as compared to a horizontal shaft crusher. This angle can be varied 15° either way but 45° is preferred since it ensures maximum conversion and enables the inlet to be positioned at a reduced elevation above the floor.

The housing is provided with a suitable ice inlet generally indicated by numeral 21 and including a horizontal portion 22. An electric motor 20 is mounted upon housing portion 23 and carries on its shaft, not shown, a V-belt pulley 26 about which are trained a plurality of V-belts 27, the latter passing about a V-belt pulley 28 on shaft 16 to drive the latter at the correct speed. A plurality of teeth 29 are mounted upon the drum and in the form of device shown the drum and wheel are adapted to be rotated counter-clockwise in Figure 2, the inlet being on the left-hand side of the machine as it is shown there, so that the drum tears into and reduces ice to a desired form. Ice crushed by the drum falls into the force imparting unit 30 which includes a plurality of blades 31 on shaft 16. The blades 31 of the wheel 18 are relieved as at 32 to permit entrance of the ice. The wheel finally throws the ice off by centrifugal force into the tangentially positioned housing outlet 33, to which is connected a hose or other suitable conduit not shown.

I have found that the ratio of the diameter of the drum to that of the wheel should be at least 1 to 1.25, and that if this is observed then the wheel will impart to the crushed ice the necessary force to result in its conveyance through the connected hose. I prefer to use even larger ratios and I have used a ratio of 1 to 1.43 successfully. Even larger ratios can be utilized although if the ratio is made too large, too large a power input may be required or the wheel may be starved of ice.

From the foregoing I believe it will be apparent that I have provided a new and novel ice crushing and blowing device, one in which for a given

horsepower output the snow-ice is delivered at a suitable distance from the device, while the machine construction employed is materially simplified.

I claim:

1. An ice crusher and slinger comprising a housing having an inlet portion, a shaft, bearings in said housing supporting said shaft at an angle of about 45° to the horizontal, means for rotating said shaft, an elongated cylindrical drum supported on said shaft and rotatable with said shaft and fitting closely in said housing, said drum having a plurality of teeth spaced about its periphery and spaced from said housing, said housing inlet opening onto the upper peripheral portion of said drum at about 90° thereto to direct a block of ice positioned in said inlet down and into gravitational engagement with said drum and the teeth on said drum to hold said ice against said teeth whereby the ice is reduced in size as said drum is rotated, an impeller wheel on said shaft in said housing below said drum to receive ice fragments from said drum which pass between said drum and said housing, said wheel having a plurality of radial blades thereon extending from said wheel toward said drum, and an outlet from said casing for ice fragments thrown off by said impeller wheel.

2. An ice crusher and slinger comprising a housing having an inlet portion, a shaft, bearings in said housing supporting said shaft at an angle of about 45° to the horizontal, means for rotating said shaft, an elongated cylindrical drum supported on said shaft and rotatable with said shaft and fitting closely in said housing, said drum having a plurality of teeth spaced about its periphery and spaced from said housing, said housing inlet opening onto the upper peripheral portion of said drum at about 90° thereto to direct a block of ice positioned in said inlet down and into gravitational engagement with said drum and the teeth on said drum to hold said ice against said teeth whereby the ice is reduced in size as said drum is rotated, an impeller wheel on said shaft in said housing below said drum to receive ice fragments from said drum which pass between said drum and said housing, said wheel being of a diameter of the order of 1.25 times the diameter of the cylindrical drum and having a plurality of radial blades thereon extending from said wheel toward said drum, and an outlet from said casing for ice fragments thrown off by said impeller wheel.

3. An ice crusher and slinger comprising a housing having an inlet portion, a shaft, bearings in said housing supporting said shaft at an angle of about 45° to the horizontal, means for rotating said shaft, an elongated cylindrical drum supported on said shaft and rotatable with said shaft and fitting closely in said housing, said drum having a plurality of teeth spaced about its periphery and spaced from said housing, said housing inlet opening onto the upper peripheral portion of said drum at about 90° thereto to direct a block of ice positioned in said inlet down and into gravitational engagement with said drum and the teeth on said drum to hold said ice against said teeth whereby the ice is reduced in size as said drum is rotated, an impeller wheel on said shaft in said housing below said drum to receive ice fragments from said drum which pass between

said drum and said housing, said wheel being of a diameter of the order of from about 1.25 to about 1.43 times the diameter of the cylindrical drum and having a plurality of radial blades thereon extending from said wheel toward said drum, and an outlet from said casing for ice fragments thrown off by said impeller wheel.

4. An ice crusher and slinger comprising a housing having an inlet portion, a shaft, bearings in said housing supporting said shaft at an angle of about 45° to the horizontal, means for rotating said shaft, an elongated cylindrical drum supported on said shaft and rotatable with said shaft and fitting closely in said housing, said drum having a plurality of teeth spaced about its periphery and spaced from said housing, said housing inlet opening onto the upper peripheral portion of said drum at about 90° thereto to direct a block of ice positioned in said inlet down and into gravitational engagement with said drum and the teeth on said drum to hold said ice against said teeth whereby the ice is reduced in size as said drum is rotated, an impeller wheel on said shaft in said housing below said drum to receive ice fragments from said drum which pass between said drum and said housing, said wheel being of a diameter of the order of 1.43 times the diameter of the cylindrical drum and having a plurality of radial blades thereon extending from said wheel toward said drum, and an outlet from said casing for ice fragments thrown off by said impeller wheel.

5. An ice crusher and slinger comprising a housing having an inlet portion, a shaft, bearings in said housing supporting said shaft at an angle of about 45° to the horizontal, means for rotating said shaft, an elongated cylindrical drum supported on said shaft and rotatable with said shaft and fitting closely in said housing, said drum having a plurality of teeth spaced about its periphery and spaced from said housing, said housing inlet opening onto the upper peripheral portion of said drum at about 90° thereto to direct a block of ice positioned in said inlet down and into gravitational engagement with said drum and the teeth on said drum to hold said ice against said teeth whereby the ice is reduced in size as said drum is rotated, an impeller wheel on said shaft in said housing below said drum to receive ice fragments from said drum which pass between said drum and said housing, said wheel having a plurality of radial blades thereon extending from said wheel toward said drum and relieved adjacent said wheel to admit ice fragments to said wheel, and an outlet from said casing for ice fragments thrown off by said impeller wheel.
